ATTORNEY.

UNITED STATES PATENT OFFICE.

EDWARD E. HEDGES, OF NEW YORK, N. Y.

APPARATUS FOR DISTILLING KEROGEN SHALE.

1,383,205.

Specification of Letters Patent. Patented June 28, 1921.

Application filed November 10, 1920. Serial No. 423,073.

To all whom it may concern:

Be it known that I, EDWARD E. HEDGES, a citizen of the United States, residing at New York, in the county of New York and State of New York, have invented certain new and useful Improvements in Apparatus for Distilling Kerogen Shale, of which the following is a specification, reference being had therein to the accompanying drawings.

10 This invention relates to apparatus for distilling kerogen shale, and other bituminous materials, and has for an object to provide an apparatus which will conduct continuous distillation of such kerogen shale and produce therefrom hydrocarbon oils substantially similar and equivalent to the crude petroleums from wells, with a dekerogenized shale, available and adapted for a base for cements of the general type known 15 as Portland cement.

A further object of the invention is to provide an apparatus for increasing the volumetric output of the lighter oils, as compared to the mere distillation of the oleaginous content found resident in the shale as mined.

A further object of the invention is to provide an improved apparatus for employing super-heated steam for commingling 25 with and reacting upon the oleaginous content.

In the dry destructive distillation of the kerogen shales it has been found that certain fixed gases pass over and carry therewith 35 a certain recoverable percentage of the light hydrocarbon oils, generally referred to as gasoline. In the dry distillation the amount of gasoline so carried over and recoverable runs four or five gallons per ton of shale, 40 whereas in employing the present apparatus, from eight to twelve gallons per ton are produced and recoverable. It is believed that this additional production of the light hydrocarbon oils is due to the liberation of 45 the molecules of otherwise heavy oil by the addition thereto of hydrogen atoms from the aqueous vapor.

The apparatus comprises a rotating retort whereby a continuous process is possible, the 50 kerogen shale entering in its natural condition at one end of the retort and discharging dekerogenized at the opposite end, the hydrocarbons passing over in the form of vapor.

55 The aqueous content is, of course con-

densed, with the hydrocarbon liquids, which requires settling to separate.

In the drawings:

Figure 1, a longitudinal diametrical sectional view through the rotating retort and its actuating means;

Fig. 2 is an end view of the retort structure from the end as indicated by arrow 2 at Fig. 1;

Fig. 3 is a sectional view on line 3—3 of Fig. 1, through one of the spirals which, at one end, is a feed and at the opposite end a discharge, the spirals being substantially identical; and

Fig. 4 is a sectional view taken on line 4—4 of Fig. 1.

Like characters of reference indicate corresponding parts throughout the several views.

The apparatus, which forms the subject matter of the present invention, comprises a drum 10, mounted to rotate in any usual and ordinary manner, as for instance, upon the idlers 11, which are, in turn, journaled upon blocks 12 capable of being raised and lowered in any approved manner, conventionally shown by the jack-screw 13, so that the drum 10 may be operated at any inclination found desirable, the inclination, of course, determining the rate of passage of the material through the drum. At one end the drum is provided with a gear 14 intergearing with a gear 15, driven in any approved manner, as by the motor 16. The motor 16 is mounted upon a base 17, which, in turn, is mounted upon a ball and socket joint 18, carried upon a foot 19, permitting the tilting of the drum by means of the elevating apparatus 13, to any inclination desired, retaining at all times the proper alignment between the gears 14 and 15. The base 17 also provides a journal 20 for the hollow trunnion 21 and contains a water jacket 22 by which the bearing of the trunnion is maintained in a cooled condition.

The drum 10 is lined with heat insulating material, shown at 23, and within such heat insulation material the kerogen shale is roasted. The drum is preferably heated by some form of electric heater, a form here shown consisting of a helical band 24, connected at one end to the insulated ring 25, and at its opposite end to the insulated ring 26. Contacts of any approved type, as the rolling contacts 27 and 28 make electrical

connections with these contact rings 25 and 26, whereby the bands 24 are heated to incandescence, or to such degree of heat as may be required within the drum. The showing 5 of the heating element as a spiral or helical band is not intended to limit the form of electrical heating element, and it is obvious that any usual or ordinary form of resistance element, connected with the contact rings, in 10 any usual and ordinary manner, will be within the knowledge of one skilled in the electrical art.

At the opposite ends, the drum is provided with worms, one of which, 29, is a feed 15 worm. This is connected at its central chamber 30 with a feed chute 31, fed from the hopper 32. The shale is introduced from the hopper 32 through the chute 31 into the central chamber 30 and by reason 20 of the rotation of the drum, the shale is carried through the spiral passage 33 (See Fig. 3) and is discharged at 34 into the periphery of the drum. The continuous feeding of the shale through the chute 31 into the central 25 chamber and through the spiral passage 33 forms a seal to prevent the escape of liberated gases which pass outwardly through the pipe 35 to any receptacle, from which the volatilized hydrocarbons, and other content of the shales, are treated in such manner as to recover the values therefrom.

At the opposite end, the worm 36 is built similar to the worm 29 but rotates relatively, in the opposite direction, actually rotating, 35 of course, synchronously with the worm 29 and the drum 10. The worm 36 is the discharge worm having an entrance at 37 and discharging into the central chamber 38, which communicates with the hollow trunnion 21, 40 discharging therefrom the spent shale. A pipe 39 extends axially through the hollow trunnion 21 and into the drum, and steam from the generator 40 is introduced through such pipe 39 into the drum 10, which, reacting 45 upon the contents, brings about results not otherwise obtainable.

In operation, the drum adjusted to the proper inclination by the manipulation of the elevating device 13, is fed with shale 50 through the chute 31 and the spiral feeder as hereinbefore described. The electric current passing through the resistance coil 24 maintains the coil in incandescent, or heated, condition. The shale is non-conductive and 55 insulation of the resistance coil from such contents is not necessary so that the shale may come in direct contact with the resistance coil. In practice it is found desirable to maintain a heat within the drum of from 60 to 750 degrees Fahrenheit. This results in the destructive distillation of the shale. At the same time, however, steam, at 60 boiler temperature, is introduced from the generator 40, but, upon being introduced into the chamber heated to from 600 to 750 de-

grees, is superheated and in such condition attacks the shale which is being agitated by the rotation of the drum. The combination of the heat from the element and the superheated steam acting upon the shale and pyrites liberates the hydrocarbon element, ammonia and sulfur.

The substances released, by volatilization, therefore contain the hydrocarbons, the molecules of some of which have been increased in hydrogen valence, the ammonia and some unchanged aqueous vapor which pass outwardly through the pipe 35 and are fractionated in any usual and ordinary manner.

The dekerogenized shales, discharged through the hollow trunnion 21, are found to be rich in oxygen which form an ideal base for combination with calcium, to produce cements of the general type known as 85 Portland cements. The by-products are therefore, the non-condensable gases produced in such quantity as to supply the motive power for generating the electricity for heating the retort and a great volume in excess, ammonia and the spent shale forming the ideal base for Portland cements. The crude oil is, of course, productive of all of the by-products usually recoverable from crude oils and perhaps others.

The apparatus above described, while ideal for the distillation of kerogen shales, is equally effective in the distillation of oil shales and other bituminous material, and the use of the term "kerogen shale" is not 100 to be considered as any limitation upon the apparatus in the treating of shales of any nature which carry hydrocarbons in any form, or of any form or compound, or combination.

What I claim to be new is:

1. A distilling apparatus comprising an inclined rotating retort, means to introduce material into the retort at the axis, and a volute feeding conduit within the retort receiving the material at the axis and discharging it at the periphery.

2. A distilling apparatus comprising an inclined rotating retort, means to introduce material into the retort at the axis, and a 115 volute feeding conduit within the retort receiving the material at the axis and discharging it at the periphery and having a plurality of convolutions about the axis between its extremities.

3. A distilling apparatus comprising an inclined rotating retort, means to introduce material into the retort at the axis, a volute feeding conduit within the retort receiving the material at the axis and discharging it at the periphery, and a volute discharge conduit within the retort moving in unison with the feeding conduit, receiving material at the periphery and discharging it through an axial orifice.

4. A distilling apparatus comprising an inclined rotating retort, means to introduce material into the retort at the axis, a volute feeding conduit within the retort receiving material at the axis and discharging it at the periphery, and a volute discharge conduit within the retort co-axial and moving in unison with the feeding conduit receiving material at the periphery and discharging it through an axial orifice.
5. A distilling apparatus comprising an inclined rotating retort, means to introduce material into the retort at the axis, a volute feeding conduit within the retort receiving the material at the axis and discharging it at the periphery and having a plurality of convolutions about the axis between its extremities, and a volute discharge conduit within the retort moving in axial unity with the feeding conduit receiving material at the periphery and discharging it through an axial orifice and having a plurality of convolutions between its extremities.
6. A distilling apparatus comprising an inclined rotating retort, a volute feeding conduit within the retort receiving material at the axis and discharging it at the periphery, a volute discharge conduit within the retort moving in axial unison with the feeding conduit receiving material at the periphery and discharging it through an axial ori-

fice, a steam inlet pipe coinciding with the discharge orifice, and a distillate conduit coinciding with the axis at the feeding end.

7. A distilling apparatus comprising an inclined rotating retort, a volute feeding conduit within the retort receiving material at the axis and discharging it at the periphery, a volute discharge conduit within the retort moving in axial unity with the feeding conduit receiving material at the periphery and discharging it through an axial orifice, and a heating element contained within the retort chamber and disposed between the feeding and discharge conduits.

8. A distilling apparatus comprising an inclined rotating retort, a volute feeding conduit receiving material at the axis and discharging it at the periphery, a volute discharge conduit moving in axial unity with the feeding conduit and receiving material at the periphery and discharging it through an axial orifice, a heating element contained wholly within the retort chamber and between the feeding and discharging conduits, a steam inlet pipe coinciding with the discharge orifice and a distillate conduit coinciding with the axis at the feeding end.

In testimony whereof I hereunto affix my signature.

EDWARD E. HEDGES.
